UNITED STATES PATENT OFFICE

ROY KLOMPARENS, OF PROVIDENCE, RHODE ISLAND

FURNACE HUMIDIFIER

Application filed December 8, 1930. Serial No. 500,795.

This invention relates generally to a furnace construction and more particularly to a humidifier adapted to be applied to the shell which surrounds the hot air type of furnace. 55 However, its use is not limited to such a construction as it may be installed in any stream of air which needs to have water vapor added thereto.

One disadvantage of humidifiers is due to the fact that they are constructed of fabric material, which rapidly deteriorates, thus becoming not only inefficient in action but also causing fouling of the air passing thereby.

I aim to overcome the above difficulties as well as attain further advantages which will be apparent from the detailed description which is to follow.

Briefly described, my invention consists of a metal plate, preferably of zigzag construction, placed in close proximity to the dome of a furnace. Means are provided for flowing water upon this plate near its top and as this water gravitates downwardly along the corrugated surface of the plate the air passes thereover and comes in contact therewith thus causing particles of water to enter the air and humidify it in a manner well known to those familiar with devices of this character. As shown in the drawing my device is applied to a furnace wall of double thickness but obviously it could as readily be applied to a single sheet metal wall.

Many other objects and purposes, with novel constructions and arrangements of parts for obtaining the same will be apparent as an understanding of the invention is had from the following description, taken in connection with the accompanying drawing, in which,

40 Fig. 1 is a side elevation, partly in cross section, of a usual hot air type of furnace equipped with my novel humidifier.

Fig. 2 is an enlarged view showing the corrugated surface of the humidifier plate together with the means for flowing water thereover, and

Fig. 3 is a cross sectional view of Fig. 2.

Similar numerals represent similar parts throughout the several views.

50 In Fig. 1, the furnace, consisting of an ash

pit 10, a fire pot 11, a dome 12 and a radiator 13, is surrounded by a cylindrical casing 15 having an opening therein, this opening adapted to be tightly closed by means of the cover plate 16.

Brackets 17 are fixed to the inner side of the closure 16 and a corrugated or zigzag plate 18 is supported by said brackets. As clearly shown in Figs. 2 and 3 the upper edge portion of the humidifier plate 18 is curved as 60 at 19 to receive the perforated pipe 20, this pipe 20 being adapted to receive a controlled flow of water through the regulating valve 21. This valve may be of any suitable type.

The lower end of the humidifying plate 65 18 is angularly formed as at 22 into a trough-like portion adapted to receive any surplus water and an outlet 23 provides an overflow therefrom.

An inner shell or casing 24 is held in position by supports 25 and has an opening therein to allow for the passage of the humidifying plate 18 together with its dependent structure. Thus the closure or plate 16 supports the entire humidifying apparatus, this plate 75 being removably held in place by means of bolts 26.

From the above it will readily be perceived that the plate 16 is a support for the entire humidifying device and that by removing the bolts 26 the same may be removed as a unit, thus providing an expedient and efficient construction.

The air freely flows around the furnace interiorly of the casing or shell and upon contact with the plate 18 tends to evaporate the water flowing thereover thus humidifying the air. Moreover, the plate 18, preferably formed of a rust proof metal, is long lived and performs efficiently over its entire period 90 of usefulness.

While I have described a complete embodiment of my invention I do not wish to be limited to the particular construction shown, my invention being in fact limited 95 solely by the attached claims.

I claim:

1. A device of the character described comprising a vertical heating unit, an outer vertical shell spaced therefrom and surround-

- ing said heating unit, an inner shell parallel to the outer shell, said inner shell being spaced from and terminating short of the ends of the outer shell whereby air may freely circulate around the inner shell, said inner and outer shells each having an opening, a closure for the opening in the outer shell and a humidifier fastened to said closure and adapted to extend inwardly of the inner shell.
- 10 2. A device of the character described in claim 1 but also characterized by the fact that the humidifier consists of an irregular surfaced metal plate adapted to receive water near its top.
- 15 3. In a furnace having a vertical heating unit surrounded by a double jacket having an opening therethrough the combination of a plate, means to fasten the plate adjacent the outside of the exterior jacket thereby tightly closing the same, brackets on the inside of the plate and extending inwardly to a point within the inner jacket, a metal plate fastened to said brackets, and means to flow water over the last named plate.
- 20 4. A furnace comprising the parts set forth in claim 3 in which the plate is vertically positioned so as to be in substantial alignment with the heating unit.
- 25 5. A furnace comprising the elements in the combination recited in claim 3 and having the metal plate therein of zigzag vertical cross section.
- 30 6. In a furnace having a vertical heating unit surrounded by a jacket having an opening therethrough the combination of a plate, means to fasten the plate over the said opening, bracket means extending from said plate into the jacket, a metal plate supported by the bracket means and means to flow water over the last named plate.

In testimony whereof I affix my signature.
ROY KLOMPARENS.
